EVERETT

UNITED STATES PATENT OFFICE.

JOHN P. JOHNSTON, OF OAK PARK, ILLINOIS, ASSIGNOR TO HIMSELF AND
EDWARD E. MORRELL, OF SAME PLACE.

LIQUID-SPRAYING DEVICE.

SPECIFICATION forming part of Letters Patent No. 662,236, dated November 20, 1900.

Application filed September 15, 1899. Serial No. 730,536. (No model.)

To all whom it may concern:

Be it known that I, JOHN P. JOHNSTON, a citizen of the United States, residing at Oak Park, county of Cook, and State of Illinois, have invented certain new and useful Improvements in Liquid-Spraying Devices, of which the following is a specification, reference being had to the accompanying drawings.

10 My invention relates to apparatus that may be used for spraying or feeding liquids of various kinds and which will efficiently spray the oil as it is introduced.

What I regard as new will be set forth in the claims.

15 In the accompanying drawings, Figure 1 is an enlarged sectional view of the liquid spraying or feeding devices, and Fig. 2 is a section on line 3 3 of Fig. 1 looking up.

20 Referring to the drawings, 18 indicates the spraying or feeding apparatus, which may be supported in any suitable manner from a feed pipe or tube 19, that will serve as an inlet or conductor for the liquid to be sprayed.

25 The spraying device or apparatus comprises a cylinder 30, having its lower end of less diameter than its upper end and carrying at its contracted lower end a nozzle 31, provided with perforations 32 for the passage 30 of the liquid. The nozzle 31 is preferably screwed upon the lower end of the cylinder to permit of its removal. At its upper end the cylinder 30 carries a head 33, screwed therein or thereupon. The head 33 is provided with an annular flange 34, which projects into the cylinder 30 and has in its lower face a series of cups or depressions 35, as shown in the drawings. Within the annular flange 34 is a hardened bearing-plate 36, having a concave channel 37, as shown in Fig. 1. The cylinder 30 is supported from the lower end of the tube 19 upon antifriction-balls 38, which run in the channel 37 and are supported by a bearing-plate 39, having a similar channel 40, as shown in Fig. 1. The bearing-plate 39 is fitted closely upon the tube 19 and rests upon a nozzle 41, screwed upon the lower end of the tube 19 and keyed thereto by a pin 42. The tube 19 is stationary,

and consequently the bearing-plate 39 is also 50 stationary.

43 indicates a hardened cylinder which is fitted upon the tube 19 near the lower end thereof and forms a bearing for the head 33, which rotates, as will be hereinafter described. 55 The head 33 is provided with an upwardly-extending annular flange 44, which receives a bushing 45, fitted closely upon the cylinder 43. The latter cylinder is held in place by a collar 46, fitted upon the tube 19 immediately 60 above the cylinder 43 and held in place by a set-screw 47, as shown in Fig. 1. By this arrangement the cylinder 43 serves as a bearing for the head 33 and takes the wear. It may be removed and replaced simply by 65 moving the collar 46 and bushing 45.

48 indicates a pipe which extends from the nozzle 41 to a point under the cups 35, said pipe extending upward to near said cups, and being inclined so that the liquid passing 70 therefrom strikes said cups tangentially and causes the head to rotate.

49 indicates a valve-stem which extends through the tube 19 from end to end, said valve-stem having at its lower end a conical 75 or needle valve 50, adapted to be seated in a suitable seat in the lower end of the nozzle 41, as shown in Fig. 1. The upper end of the valve-stem 49 passes beyond the upper end of the tube 19 and may be provided with 80 a hand-wheel. (Not shown.)

The operation of this feeding and spraying apparatus is as follows: The feeding device being in the proper position liquid is introduced to tube 19, down which it flows under 85 a pressure of from fifteen to eighty pounds to the square inch when oil is to be sprayed. A small part of the liquid, usually about one-third of the quantity to be supplied, passes down through the nozzle 41, the needle-valve 90 being properly adjusted to that end by operating its hand-wheel. The remaining two-thirds passes through pipe 48 and is discharged with considerable force, depending on the pressure, into the cups 35, causing 95 the head 33 to rotate in the direction indicated by the arrow in Fig. 2. The rotation of the head spreads the liquid over the in-

terior surface of the cylinder 30, which rotates with the head 33. The rotation of the cylinder serves to scatter the liquid and causes it to hug the interior surface thereof. 5 The liquid gradually passes down and out through the holes 32 of the nozzle 31 and is sprayed by the rotation of said nozzle.

If when the apparatus is in operation it should be found that the proper quantity of 10 liquid is not being supplied, the quantity may be varied without changing the pressure by adjusting the needle-valve 50, and in practice I have found that said valve provides a sufficient degree of variation for all practical 15 purposes, so that it is practically never necessary to vary the pressure of the liquid in order to properly regulate the quantity of liquid supplied. To adapt the apparatus for purposes requiring a very much greater or 20 less quantity of liquid, it is necessary simply to vary the size of the pipe 48 through which the liquid is discharged against the cups; but under ordinary circumstances all necessary variation may be secured by simply adjusting the needle-valve. 25

My invention includes such alterations and modifications as would occur to those familiar with the art and is not limited to the specific devices or arrangement illustrated and described except in so far as such features are 30 specifically claimed.

That which I claim as my invention, and desire to secure by Letters Patent, is—

1. In a liquid-spraying apparatus, the combination of a feed-pipe, a rotary cylinder, means for rotating said cylinder by the flow of the liquid thereinto, one or more passages for the discharge of the liquid from said cylinder, and means for varying the quantity of 35 liquid supplied to said cylinder without varying the speed of its rotation, substantially as described.

2. In a liquid-spraying apparatus, the combination of a feed-pipe, a rotary cylinder, means for injecting liquid tangentially into 45 said cylinder to effect its rotation, additional means for supplying liquid to said cylinder, and one or more passages for the discharge of liquid from said cylinder, substantially as described.

3. In a liquid-spraying apparatus, the combination of a feed-pipe, a rotary cylinder, means operated by the flow of the liquid thereinto for rotating said cylinder, additional 55 means for supplying liquid to said cylinder, and one or more passages for the discharge of the liquid from said cylinder, substantially as described.

4. In a liquid-feeding apparatus, the combination of a spraying device operated by the flow of liquid, means for supplying liquid under pressure to said spraying device, and means for varying the quantity of liquid supplied to the spraying device without varying

the pressure of the liquid therein, substantially as described. 65

5. In a liquid-feeding apparatus, the combination of a spraying device, means for conducting liquid to said spraying device, a plurality of passages for admitting liquid to said spraying device, and a valve governing the admission of liquid to one of said passages and not another, substantially as described. 70

6. In a liquid-feeding apparatus, the combination of a rotary cylinder, a supply-pipe, a 75 plurality of passages for admitting liquid from said pipe to said cylinder, and a valve governing the admission of liquid to one of said passages and not another, substantially as described. 80

7. In a liquid-feeding apparatus the combination of a spraying device, means for conducting liquid to said spraying device, a plurality of passages for admitting liquid to said spraying device, a valve governing the admission of liquid to one of said passages and not another, and means for operating said spraying device by the flow of liquid, substantially as described. 85

8. In a liquid-feeding apparatus, the combination of a rotary cylinder, a supply-pipe for conducting liquid to said cylinder, means for injecting liquid into said cylinder tangentially, separate means for discharging liquid into said cylinder, and a valve for controlling the latter discharge, substantially as described. 90

9. In a liquid-feeding apparatus, the combination of a rotary cylinder having an outlet or outlets for the discharge of liquid at or near 100 the lower end of the cylinder, a pipe communicating with said cylinder for supplying liquid thereto, means operated by the flow of liquid for rotating said cylinder, and ball-bearings supporting said cylinder from said 105 supply-pipe, substantially as described.

10. In a liquid-feeding apparatus, the combination of a rotary cylinder having a series of cups annularly arranged, a supply-pipe, and a pipe affording communication between 110 said supply-pipe and said cylinder and arranged to discharge liquid from said pipe into said cups tangentially, substantially as described.

11. In a liquid-feeding apparatus, the combination of a rotary cylinder having a series of cups annularly arranged, a supply-pipe, a pipe affording communication between said supply-pipe and said cylinder and arranged to discharge liquid from said pipe into said 115 cups tangentially, and a separate valved passage between said supply-pipe and said cylinder, substantially as described.

12. In a liquid-feeding apparatus, the combination of a supply-pipe having an external 120 sleeve fitted upon the lower end thereof, a rotary cylinder having its upper end fitted upon said sleeve, bearings supporting said cylinder, 125

der and permitting its rotation, and means for discharging liquid from said supply-pipe tangentially into said cylinder, substantially as described.

5 13. In a liquid-spraying apparatus, the combination of a rotary spraying-head adapted to contain the liquid to be sprayed, means for supplying liquid thereto, one or more passages

for the discharge of the liquid from said head, and means operated by a part only of the liquid supplied to said spraying-head for rotating said head, substantially as described.
